UNITED STATES PATENT OFFICE

WINTHROP L. JACOBS, OF JERSEY CITY, NEW JERSEY, ASSIGNOR TO HAK
FORD CARPET COMPANY, OF HARTFORD, CONNECTICUT.

DESIGN FOR CARPET.

SPECIFICATION forming part of Design No. 12,208, dated March 29, 1881.

Application filed February 10, 1881. Term of patent 3½ years.

To all whom it may concern:

Be it known that I, WINTHROP L. JACOBS, of Jersey City, in the county of Hudson and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure A resembles leaves surrounding and growing out of a shield-shaped center, and is connected by a stem with the circular flower-like figure m, which is also connected with the serrated figure H, and has projecting from it the flower-figure g, and the branch n with flowers thereon. This branch n extends toward the figure E, resembling a large bud, which is connected by a stem with the circular figure d.

On a stem projecting from the figure d is another bud-like figure, b, and a similar stem connects the figure d with the circular deeply-serrated figure K.

From the stem connecting d and A grows the branch-like figure R, and also the figure i, composed of smaller rectangular figures.

The figure D is a flower-like figure, from which extends the budding branch F.

On a stem extending from D is set the flower-figure G, and from the same stem projects the figure a, joined by a stem to the circular serrated figure H, also connected by a stem with the leaf-like figure P.

The triangular serrated figure I is set on the stem, from which grows also the leaf-like figure J, connected by the same stem to the figure K.

M is a flowering branch-like figure, and p is a flower-figure on a stem near the figure M.

N is a circular-patterned figure, having near it the oval figure q, made up of smaller figures. A somewhat similar figure, f, is set on a stem connecting it with the figure L, having pointed projections at its corners.

C is a circular rosette-shaped figure.

B is a figure consisting of a center surrounded by branching leaves and flowers, having near it the flowering branch Q, and connected by a stem with the branch h. From this same stem projects the leaf-like figure O.

The whole design is on a patterned background consisting of rectangles within small circles, and gives the effect of vines or stems running irregularly across the background, and bearing on them the figures described.

I claim—

1. The design for carpets, consisting of the figure A, substantially as shown.
2. The design for carpets, consisting of the figure B, substantially as shown.
3. The design for carpets, consisting of the figure C, substantially as shown.
4. The design for carpets, consisting of the figure L, substantially as shown.
5. The design for carpets, consisting of the figure R, substantially as shown.
6. The design for carpets, consisting of the figures A q m n E d b R i K, substantially as shown.
7. The design for carpets, consisting of the figure i, substantially as shown.
8. The design for carpets, consisting of the figure M, substantially as shown.
9. The design for carpets, consisting of the figure K, substantially as described.
10. The design for carpets, consisting of the figure D, substantially as shown.
11. The design for carpets, consisting of the figure G, substantially as shown.
12. The design for carpets, consisting of the figures J 1 D F G a H, substantially as shown.
13. The design for carpets, consisting of the figure F, substantially as shown.
14. The design for carpets, consisting of the figure N, substantially as shown.
15. The design for carpets, consisting of the figure f, substantially as shown.
16. The design for carpets, consisting of the figures B h O Q, substantially as shown.
17. The design for carpets, consisting of the figure P, substantially as shown.
18. The design for carpets, consisting of the figures B Q L, substantially as shown.
